UNITED STATES PATENT OFFICE.

SAMUEL ODGERS AND PETER LA PIERRE, OF KANSAS CITY, MISSOURI.

FIRE-ESCAPE.

1,277,339.

Specification of Letters Patent. Patented Aug. 27, 1918.

Application filed October 13, 1917. Serial No. 196,443.

To all whom it may concern:

Be it known that we, SAMUEL ODGERS and PETER LA PIERRE, citizens of the United States, residing at Kansas City, in the county of Jackson and State of Missouri, have invented new and useful Improvements in Fire-Escapes, of which the following is a specification.

This invention relates to new and useful improvements in fire escapes, and the principal object of the invention is to provide a car or receptacle with means for lowering the same, and means for controlling the lowering means by the person within the car.

Another object of the invention is to provide a box within the room for containing the parts of the apparatus when not in use with means for attaching the supporting bar permanently to said box.

A further object of the invention is to provide a novel form of car or receptacle which will conveniently support a person therein and one which may be folded so it will occupy but a little space when in the box.

Another object of the invention is to provide a device of this character which is simple and durable in construction, reliable and efficient in operation and one which can be manufactured and placed upon the market at a minimum cost.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation of a building showing my invention applied thereto.

Fig. 2 is a sectional view thereof.

Fig. 3 is a sectional view through the safety or operating pulleys.

Fig. 4 is an end view of the brake mechanism.

In these drawings 1 indicates the box located within the room adjacent the window, and this box is adapted to receive the parts of the apparatus when the same is not in use. 2 indicates a beam having its

inner end suitably connected with the box, as by means of the flexible connection 3, and said beam, when the apparatus is being used, is adapted to lie across the window sill with its free end projecting beyond the same. This beam is provided with a bent strap 4, forming a hand-hold and having one part projecting beyond the beam and provided with an enlargement 5 which bears against the outer part of the window sill. The free end of the beam is provided with a ring which is to receive the pulley 6 through which the cable 7 is to pass. The car or receptacle indicated by the numeral 8 has its upper part formed cylindrical in shape and preferably of a suitable metal. The bottom of the car is provided with an opening 10, the remaining portion 9 of said bottom serving as a seat, and a flexible member 11, preferably formed of canvas, is secured around said opening and forms an extension to the car and is adapted to receive the feet of a person sitting in the car. The car has secured to its upper edges, a bail 12, preferably made of rope or the like and this bail has secured thereto a pulley 13. The front of the car has secured thereto a frame work 14 formed of two pieces of metal spaced apart and carrying a pair of pins 15 and 16. A grooved roller 17 is mounted on the upper pin 15 while a double lever 18 is pivoted mid-way of its ends on the other pin 16. This double lever has journaled therein a grooved roller 19 which is adapted to co-act with the roller 17 to form a brake for the car. One end of the cable 7 is secured to the bail or a stationary part of the pulley 13 and then said cable passes around the pulley 6 and then downwardly through the sheave of the pulley 13, then through the braking rollers, through the bottom of the car and thence to the ground. If desired said cable may be made of sufficient length so that it may be carried upwardly again and secured to the bottom of the car. It will thus be seen that when a person is sitting within the car his weight will cause the same to move downwardly and this movement may be controlled by means of the braking rollers which he may actuate by means of the lever 18, which is in easy reach of a person sitting in the car. When a person reaches the ground he may return the car to the window by simply pulling on the rope, or if desired a counter-weight 20 may be provided on said rope, so

that the car is automatically returned to the window.

When the device is to be used the car with the rope attached thereto is first removed from the box and lifted out of the window. This will throw the beam 2 across the window sill in proper position.

It is thought from the foregoing description that the advantages and novel features 10 of my invention will be readily apparent.

I desire it to be understood that I may make slight changes in the construction and in the combination and arrangement of the several parts, provided that such changes 15 fall within the scope of the appended claims.

What I claim is:—

1. A fire escape comprising a car formed of metal and having an opening in its bottom, a canvas extension surrounding said opening, a supporting beam, a pulley on said beam, a cable having one end connected

with the car and passing through said pulley and having its other end connected with the canvas extension, and a weight on said cable, said weight, when the car is suspended from a window, dropping through the opening and the canvas extension and straightening the cable.

2. A fire escape comprising a holding receptacle adjacent the window, a supporting beam movably secured to said receptacle, a curved hand-grip connected with said beam and having its lower end extended to engage the window-sill to hold the beam above the same, a pulley carried by the end of said beam, a cable engaging said pulley, and a car connected with said cable, all of said parts occupying the receptacle when not in use.

In testimony whereof we affix our signatures.

SAMUEL ODGERS.
PETER LA PIERRE.
